United States Patent Office

Des. 213,907
Patented Apr. 22, 1969

213,907

KEYHOLDER

Cecil B. Woofter, 603 E. 18th N. Newton, Iowa 50208
Filed Nov. 29, 1967, Ser. No. 9,585

Term of patent 14 years

Int. Cl. D8—03

U.S. Cl. D87—8

FIG. 1.

FIG. 2.

FIG. 3.

FIG. 5.

FIG. 4.

FIGURE 1 is a front elevation view of my design for a keyholder;

FIGURE 2 is a side elevation view;

FIGURE 3 is a top plan view;

FIGURE 4 is a bottom plan view;

FIGURE 5 is a side elevation sectional view taken along the line 5—5 of FIGURE 4.

The front and rear views are identical.

I claim:

The ornamental design for a keyholder, as shown and described.
